(57) **CLAIM**

The ornamental design for access door/tray for facsimile machine, as shown and described.

DESCRIPTION

FIG. 1 is a front view of an access door/tray for facsimile machine with the access door/tray in a retracted position;

FIG. 2 is a top view thereof;

FIG. 3 is a perspective view thereof;

FIG. 4 is a perspective view thereof with the access door/tray in a partially extended position;

FIG. 5 is a front view thereof with the access door/tray in a partially extended position;

FIG. 6 is a top view thereof with the access door/tray in a partially extended position;

FIG. 7 is a bottom view thereof with the access door/tray in a partially extended position;

FIG. 8 is a left side view thereof with the access door/tray in a partially extended position;

FIG. 9 is a right side view thereof with the access door/tray in a partially extended position;

FIG. 10 is a perspective view thereof with the access door/tray in a fully extended position;

FIG. 11 is a front view thereof with the access door/tray in a fully extended position;

FIG. 12 is a top view thereof with the access door/tray in a fully extended position;

FIG. 13 is a bottom view thereof with the access door/tray in a fully extended position;

FIG. 14 is a left side view thereof with the access door/tray in a fully extended position; and,

FIG. 15 is a right-side view thereof with the access door/tray in a fully extended position.

The rear view with the access door/tray in the retracted, partially extended, and fully extended positions, and the left, right and bottom views with the access door/tray in the retracted position, contain no ornamentality and are omitted.

The broken lines define the bounds of the claimed design but do not form part of the claimed design.
